UNITED STATES PATENT OFFICE.

JOHN LINDALL, OF MEDFORD, AND JAMES F. WHITE AND PATRICK HARRINGTON, OF BOSTON, MASSACHUSETTS.

SNOW-PLOW.

SPECIFICATION forming part of Letters Patent No. 651,531, dated June 12, 1900.

Application filed January 2, 1900. Serial No. 158. (No model.)

To all whom it may concern:

Be it known that we, JOHN LINDALL, of Medford, county of Middlesex, and JAMES F. WHITE and PATRICK HARRINGTON, of Boston, county of Suffolk, State of Massachusetts, have invented an Improvement in Snow-Plows, of which the following description, in connection with the accompanying drawings, is a specification, like letters on the drawings 10 representing like parts.

The present invention relates to a snow-plow and is embodied in a snow-plow of the kind commonly used in street-railway work, in which the snow is cleared away from the track 15 by means of a blade or scraper extending diagonally across the track underneath the body of the plow. In a plow of this description the snow-removing blade is commonly provided at its rear end with an extension known 20 as the "outrigger" or "leveler," the object of which is to level the heap of snow thrown off the track by the main portion of the blade, so that the said snow will not be heaped up too 25 near the track, where it will be in the way of the steps or bodies of the cars. It is not essential or desirable that the outrigger should be held firmly against the ground, and, in fact, it is necessary that the said outrigger at 30 times be brought close to the body of the plow, so as to clear obstacles which may be close to the track. Furthermore, as the object of the 35 outrigger is merely to level to a greater or less extent the pile of snow it is desirable to avoid the additional resistance which would be encountered if the said outrigger were always held close to the ground when there is a very large body of snow to be removed. The outrigger therefore is pivotally connected with the end of the main blade, so that it 40 can be lifted to a vertical position when desired, and it has been customary heretofore to hold the outrigger in place when there is sufficient snow to cause it to otherwise lift up by actually standing upon the outrigger itself. This custom has been objected to on 45 account of the danger to the employees; and it is the object of the present invention to provide the outrigger with means for yieldingly holding it in position, as is necessary, 50 said means being operated from the body of the plow. This is accomplished in accord-

ance with the present invention by providing the outrigger with a controller pivotally connected therewith and extending upward therefrom, the said controller having a suitable guide upon the body of the plow and being yieldingly connected therewith in any suitable way.

Figure 1 is a partial side elevation of a snow-plow embodying the invention. Fig. 2 is a partial end elevation of the same, and Fig. 3 a side elevation showing a modification.

The snow-plow is provided with the ordinary scraper-blade *a*, extending diagonally across the track under the plow-body, and the said blade is provided with the outrigger *b*, pivotally connected thereto at *b*², the said outrigger being shown as provided with a lifting-rope *b*³, by means of which it may be lifted from the track and thrown up toward the body of the plow. To keep the outrigger pressed down upon the pile of snow when the plow is in use and at the same time leave the said outrigger capable of yielding when the mass of snow is too great to be entirely pushed aside, the said outrigger is shown as provided with a controlling member *c*, pivotally connected at *b*⁴ with the outrigger *b*, the said controlling member being shown as a rod having a guide *c*² somewhere upon the body *A* of the plow, so that it is maintained in a nearly vertical position, as indicated. It is obvious, therefore, that a downward-yielding pressure upon the said controlling member will keep the outrigger in its operative position substantially as it would be kept in position by the weight of a man standing directly upon the outrigger itself. The yielding downward pressure upon the controller *c* may be provided for in any suitable or usual way, the said controller being shown in Figs. 1 and 2 as provided with a flexible connecting member *d*, which may be yieldingly secured in position in any suitable or usual way. The said member *d* may be connected with a lever *e*, provided with a treadle portion *e*², the said treadle portion being over the platform or floor of the plow, so that one of the men running the plow can stand upon the said treadle without leaving the plow, thus by his own weight holding down the outrigger and

being capable of exercising his judgment as to releasing the same exactly as if he were standing upon the outrigger itself.

While the construction shown in Figs. 1 and 2 is desirable, owing to the fact that the downward pressure can be effectually regulated in accordance with the judgment of the operator substantially as if he were standing on the outrigger itself, it is obvious that the means for holding the controller *c* may be modified without departing from the invention. As shown in Fig. 3, for example, the said controller is provided with a guide-collar *c²¹*, working on a stationary vertical guide *c²⁰*, connected with the plow-body, and the said collar is provided with a flexible connecting member *d¹⁰*, adapted to be wound upon a windlass *e¹⁰*, provided with an operating-wheel *e²⁰*. The said connection is further shown as provided with a spring *d¹²*, so that if desired the windlass may be locked, permitting the outrigger to play up and down within the limits provided for by the spring, or, if there is considerable snow, so that it may be desirable to permit the outrigger to lift to a considerable extent at times, it may be held in place by manually controlling the operating-wheel, which can be continually held by the operator and permitted to yield in accordance with varying conditions.

It is obvious that the specific construction and arrangement of the controller and its actu-

ating mechanism may be variously modified without departing from the invention.

We claim—

1. In a snow-plow, the combination with the diagonal scraper-blade; of an outrigger or leveler pivotally connected therewith; a controlling-rod extending upward from said leveler toward the body of the plow; a guide for the said rod connected with the body of the plow and an actuating device for yieldingly pressing the said rod downward to keep the outrigger in operative position, substantially as described.

2. In a snow-plow, the combination with the transverse scraper-blade; of an outrigger pivotally connected therewith; controlling-rod pivotally connected with said outrigger and projecting upward toward the body of the plow; a guide for the said rod connected with the body of the plow; and a lever also connected with said rod for producing a downward movement thereof, substantially as described.

In testimony whereof we have signed our names to this specification in the presence of two subscribing witnesses.

JOHN LINDALL.
